CONTROL OPERATING

John T. Nichols, Pittsburgh, Pa.

Application November 14, 1932, Serial No. 642,671

1 Claim. (Cl. 236—74)

This invention relates to devices automatically operating controls to maintain conditions affected thereby within determined ranges. One object is to provide a device which will operate a control to hunt a resting point best suited for the maintenance of such a range. Other objects may be inferred from the following exemplary disclosure of the invention applied to a furnace fuel valve to maintain a determined range of furnace temperatures.

10 Referring to the drawing:

Figure 1 is a schematic drawing of the invention.

Figure 2 is a detail from the first figure.

15 A furnace fuel control valve 1 is operated by a reversing electric motor 2 through a gear reduction unit 3. The motor 2 is controlled by a pyrometric switch which includes a movable contact 4 and fixed contacts 5 and 6. These contacts are energized by power lines 7 and 8, line 7 being connected to the right hand contact 5 through a solenoid 9 and to the left hand contact 6 through a solenoid 10, and the line 8 to the central movable contact 4.

20 This pyrometric switch is arranged for operation when a range of temperatures is exceeded by a furnace whose fuel supply is controlled by the valve 1. When the temperatures drop below this range the movable contact 4 closes with the right hand fixed contact 5, and when the temperatures rise above this range this movable contact closes with the left hand fixed contact 6. The solenoids 9 and 10 are thereby selectively energized according to the conditions in the furnace. These solenoids each operate a bank of switches associated therewith, by respective attraction of the armatures 9^a and 10^a.

25 When the temperature rises above the range the contacts 4 and 6 of the pyrometric switch close so that the solenoid 10 is energized and its operating armature attracted. This closes a contact 11 and energizes the motor 2 so that it operates to drive the valve 1 in a closing direction. This circuit is effected through the lines 7 and 8, the line 8 being then connected through the line 11^a to drive the motor 2 in this direction.

30 The operating shaft 1^a of the valve 1 extends through and beyond the gear reduction unit 3 and carries a brush contactor 12 energized by the line 8 through a suitable collector. This brush contactor cooperates with a commutator member 13 driven by a motor 14 through a gear reduction unit 15 at a much slower speed than the valve operates.

35 A contact 16 closes simultaneously with the

5 contact 11 and energizes this motor 14 to drive the commutator element 13 in the same direction the brush contactor 12 is moved. This brush contactor moves with the control valve 1, as it is carried directly by the latter's operating shaft. This commutator element carries separated arcuate contacting segments 13^a and 13^b which communicate with lines 17 and 18 through suitable collector elements.

10 As the furnace's temperature is brought within the desired range the contacts 4 and 6 break the circuit to the solenoid 10 and the armature 10^a is released. This opens the contacts 11 and 16 and stops the motors 2 and 14. The release of this armature also closes contacts 19 and 20 15 so that a circuit is established to the motor 2 through the lines 19^a, 20^a, closed switches 21 and 22, lines 17 and 18, commutator segments 13^a and 13^b, brush 12 and line 8. As the brush 12 is rotated faster than the commutator elements 13 it will be on the latter's segment 13^a so that 20 the motor 2 is circuited for reverse operation to that of its operation by the pyrometric switch. This turns the valve in an opening direction until the brush 12 is brought to the dead spot between 25 the commutator's segments 13^a and 13^b.

30 When the temperature falls the contacts 4 and 5 of the pyrometric switch are closed so that the solenoid 9 is energized and its operating armature attracted. This closes contacts 23 and 24 and opens 21 and 22 and operates the motor to open the valve 1. This is circuited similarly to the switches associated with the contacts 4 and 6 except that the two motors are reversed. When the temperature is again within the desired range 35 the contacts 4 and 5 open and the solenoid 9 de-energized, thus bringing the motor 2 under the control of these commutator and brush elements. In this case, however, the brush contactor 12 will be on the segment 13^b of the commutator element so that the motor 2 is operated in a valve closing direction. As soon as the brush contactor reaches the commutator's dead spot the motor 2 stops and the valve 1 rests.

40 If a pyrometric switch is used to control a furnace valve it is necessary to arbitrarily return the valve to a resting position when not under this switch's control. If this point is set, it is impossible to compensate for varying furnace loads and the motor controlling the valve must be constantly in motion. By the use of the control here disclosed the valve automatically hunts a resting position which compensates for varying loads in the furnace.

45 The specific example shown and described is in 55

accordance with the patent statutes and is not for the purpose of limiting the invention specifically thereto. For instance, the brush contactor and commutator elements may be substituted by cam-actuated switch elements, etc., and the circuits varied considerably without departing from the inventive idea.

5 **I claim:**

The combination of a control, a reversing electric motor driving said control, means for con-

necting said motor when the extremes of a range of conditions affected by said control are exceeded, and means including cooperative elements respectively moving at the same and reduced speeds as said controller for reversely connecting said motor when disconnected by said first means, said elements being constructed and arranged to disconnect said motor when they are respectively moved to determined mutual positions.

JOHN T. NICHOLS. 10
